ATTORNEYS.

UNITED STATES PATENT OFFICE.

EDGAR D. ROMANS, OF ST. PAUL, MINNESOTA, ASSIGNOR TO GRANT WALDREF, OF ST. PAUL, MINNESOTA.

MANIFOLD BRACKET.

1,417,691.

Specification of Letters Patent. Patented May 30, 1922.

Application filed November 16, 1920. Serial No. 424,418.

To all whom it may concern:

Be it known that I, EDGAR D. ROMANS, a citizen of the United States, residing at St. Paul, in the county of Ramsey and State of Minnesota, have invented a new and useful Manifold Bracket, of which the following is a specification.

This invention relates to improvements in manifold brackets for hydraulic hoists, the 10 primary object being to provide a bracket which will form a combined support for a pump below the hoist, the clutch for transmitting driving power from the main driving shaft of the vehicle to the pump and the 15 actuating device for throwing the clutch into and out of connection with the driving element of the clutch on the shaft and form a connection between the pump and the hoisting cylinder for the impelling liquid. Heretofore trouble has been encountered in 20 constructing manifold brackets of the class stated, from blow holes in the material constituting the bracket, which, owing to the high pressure of impelling liquid employed 25 for lifting heavy loads, weaken the material to a point at which openings occur and permit the impelling liquid to leak and escape, thus rendering the apparatus ineffective or 30 at best inefficient and troublesome. My invention primarily is designed to overcome this objection in a simple and inexpensive manner.

My invention further enables the parts mentioned to be arranged and assembled in 35 compact form, thereby economizing space, producing greater efficiency and effectiveness in operation of the working parts and unifying the structure as a whole so as to simplify and reduce tendency of the parts 40 getting out of running order. The unification of the parts also reduces cost of production and saves time and material in applying the parts to a motor truck for use.

With these and other objects and advantages in view, my invention comprises the features of construction and combination of parts hereinafter particularly described and claimed.

In the accompanying drawing forming 50 part of this specification, Fig. 1 is an elevation showing a detail of the lower end of a hydraulic hoisting cylinder mounted on its support and to which my invention is shown applied, the drive shaft of the vehicle being 55 shown; Fig. 2 is a perspective view of my

improved manifold bracket when removed from the vehicle, and Fig. 3 is a cross section taken along a line 3-3 in Fig. 2.

In the drawing, A indicates the lower end of a hydraulic hoist cylinder which is commonly employed upon motor trucks for raising and lowering the truck body into and out of dumping position. The lower end of this cylinder is shown provided with the usual combined cylinder end and base 10, which is supported upon the chassis of the motor truck in the usual manner, such as by angle bars 11. B indicates the longitudinal main drive shaft of the vehicle, which transmits power from the prime mover to the rear 60 wheels for propelling the vehicle.

In operating the hoist, impelling liquid is employed, such as oil or other liquid, which is forced upwardly under great pressure into the lower end of the cylinder and projects 70 the piston therein, said impelling liquid being forced by a pump C of gear type or any other construction. This pump has the usual pump casing 12 containing an outlet port 13, through which the impelling liquid 80 is projected and valve mechanism 14 connected with an ingress or return duct 15 leading from the upper end of the cylinder above the piston, said valve casing being provided with a valve operating shaft 16 which is operated by the crank arm 17 and connecting rod 18 leading upwardly to a convenient position for the operator to actuate. The pump also has a main driving shaft 19 for 85 actuating its fluid impelling gears, said shaft 90 being shown operated by a sprocket wheel 20, although it may be operated by any actuating device. The parts described are all of ordinary construction common to hydraulic hoists for dumping bodies.

Power for driving the pump originates in the drive shaft B of the vehicle and is connected with the pump by a clutch D, a driving sprocket 21 in alignment with sprocket 20 and a chain belt 22 traveling 100 over said sprockets. The clutch has the usual shifting fork 23 mounted upon the rock shaft 24, said rock shaft being turned by the arm 25 and actuating rod 26 for shifting the clutch to actuate or stop the pump.

My improved manifold bracket E consists of a skeleton frame, which, as illustrated, is of rectangular form, the outer frame portion being formed with a top plate 40, which is secured to the lower surface of the com- 105 110

bined cylinder end and support 10 by means of bolts 41, or other means. The frame of the manifold bracket has a body portion 43 resembling a web depending from the plate 40, at the lower end of which and at one side of the shaft B, free from the clutch, is a horizontal, rectangular plate 44, to the lower surface of which the pump C is secured by bolts 45, or other means. The side 10 of the web or body 43 is formed with bearings 46 in which the rock shaft 24 is journaled in transverse position above the clutch and shaft B. Thus, the manifold bracket is designed to support the pump and the rock 15 shaft in convenient position to be driven by the drive shaft and to actuate the clutch.

The manifold bracket is also formed with a duct or channel 47 traversing the web and connecting the lower end of the cylinder 20 through the end plate and support 10 with the port 13 in the pump C. The material of the web is enlarged around the duct 47, a flanged boss 48 being formed on the opposite sides of the web to re-enforce the 25 strength of the web and to minimize the amount of material necessary in producing a strong and durable structure. As stated in the introduction to this specification, considerable trouble has been encountered from 30 leaks occurring through the wall of the duct which connects the cylinder with the pump for transmitting the impelling liquid. This objection I have overcome by casting a thin tube 49 into the manifold bracket in position to line the duct 47. This tube may be made out of thin steel or other material of a higher melting temperature and finer quality of material than that constituting the bracket, thus reducing likelihood of 35 40 leaking through the wall of the duct as heretofore. The tube lining may be of any shape desired and enables the use of lower grade material constituting the bracket than

heretofore. An intimate bond between the lining and wall of the casing, forming the 45 passage between the cylinder and pump, is produced by casting the material of the bracket around the tube.

Having described my invention, what I claim as new and desire to secure by Letters Patent is:

1. In combination with a hoist cylinder, a bracket at the lower end of said cylinder and a pump supported by said bracket, said bracket being formed with a duct having an 55 anti-leaking lining therein forming a connection between the cylinder and the pump.

2. In combination with a hoist cylinder, a bracket at the lower end of said cylinder, a pump supported by said bracket, and an 60 anti-leaking tube incorporated into said bracket and forming a connection between said cylinder and pump.

3. A manifold bracket for the cylinder and pump of a hydraulic hoist, consisting of 65 a depending web having a lateral fastening plate at its upper end and a pump supporting plate at its lower end disposed in offset position below the upper plate and an anti-leaking tube incorporated into said web and 70 opening upwardly and downwardly respectively through said upper and lower plates.

4. A manifold bracket for the cylinder and pump of a hydraulic hoist, consisting of a depending web having a lateral fastening plate at its upper end, a pump supporting plate at its lower end disposed in offset position below the upper plate and bearings 75 on the side of said web in which an actuating shaft may be journaled, and an anti-leaking tube incorporated into said web and opening upwardly and downwardly respectively through said upper and lower plates.

In testimony whereof, I have signed my name to this specification.

EDGAR D. ROMANS.
